UNITED STATES PATENT OFFICE.

SAMUEL TURNER AND THOMAS EASTAUGH, OF ROCHDALE, ENGLAND, ASSIGNORS TO
SAMUEL TURNER & COMPANY, LIMITED, OF SPOTLAND, ROCHDALE, ENGLAND.

LOOM FOR WEAVING.

Application filed September 26, 1928, Serial No. 308,393, and in Great Britain July 2, 1927.

This invention relates to looms for weaving with more particular reference to those which are fitted with automatic weft replenishing mechanism.

5 A disadvantage of such existing mechanism lies in the fact that the shuttle requires to be very firmly held in the shuttle box while transfer is taking place and in consequence a stronger pick and considerably more power is required to operate the shuttle than would be needed for the normal 10 operation of the loom.

According to the present invention, therefore, we discriminate between the normal 15 operation of the loom and its operation during transfer by providing means for retaining a firmer hold upon the shuttle during the moment of transfer, which means is inoperative during the normal working of the 20 machine so that the additional holding of the shuttle is effective only at the moment when such is required, that is, at the moment of transfer.

The accompanying drawings illustrate one 25 mode of carrying out the invention:—

Figure 1 is a more or less diagrammatic plan showing the breast beam of a loom and sley with parts mounted and arranged thereon in accordance with the invention;

30 Figure 2 is a rear elevation of the end of the sley at the transfer end of the loom, and

Figures 3 and 4 are two views on a larger scale showing a detail.

35 In carrying our invention into effect we may apply our improvements to existing looms or to looms specially built for the purpose, and such looms are provided with the usual accessories incidental to weft replenishing looms, that is to say, with some 40 form of magazine (not shown) for the cops and with a transerrer on a hammer shaft for the purpose of pushing a full cop into the shuttle and simultaneously ejecting 45 therefrom the empty cop whenever the weft requires replenishing.

We also provide the usual weft fork and hammer mechanism (not shown) for bringing into operation the weft replenishing 50 means such as is commonly employed on automatic weft replenishing looms.

Further, we provide upon the transfer shaft e' a cam n adapted to operate the swell or other device p for holding the shuttle 5 in the shuttle box at the moment when a

transfer is to be effected, so that the shuttle will be more firmly held in position at this moment than during the normal operation of the loom so that in this way an easier pick and less power will be required to drive the shuttle than is ordinarily needed in connection with weft replenishing looms. Thus, for example, the cam n (which may be loose on the transfer shaft e' and operated by a collar n' on said shaft) may operate upon the spring-controlled lever o (Figures 1 and 4) which is pivoted at 6 and normally retained in inoperative position by a spring 7 and which in turn acts upon the swell p to cause the latter to hold the shuttle firmly in position during transfer, the swell being held in its normal position by the spring arm o' . In this way, we are able to employ an easier pick requiring comparatively little power during the normal working of the 75 loom while during the moment of transfer the shuttle is firmly held until the transfer is completed whereupon the shuttle is held only by the swell.

A further improvement in accordance 80 with our invention has for its object to prevent damage to the shuttle such as frequently occurs in connection with ordinary weft replenishing looms owing to the full pirn which is being inserted into the shuttle 85 riding upon the side thereof, and in accordance with our invention this fault is obviated by providing a bar w , baffle, dwarf wall or other like fitting or attachment upon the front of the shuttle box on the replenishing side of the loom.

It will be understood that the invention is not to be limited to the foregoing details of construction which are given by way of example only, nor is it to be limited to any 95 particular type or construction of weft replenishing loom to which it is to be applied.

Having now described our invention, what we claim as new and desire to secure by Letters Patent is:—

1. In an automatic weft replenishing loom, the combination with the shuttle box of a swell for checking the shuttle, a spring member for holding the swell in a normal checking position, a transfer shaft, and 105 means operable upon rotation of the transfer shaft for moving said swell into engagement with the shuttle during the transfer operation.

2. A checking mechanism as claimed in 110

claim 1 said means comprising a pivoted lever and spring means for normally holding said lever out of engagement with the swell.

- 5 3. A checking mechanism as claimed in claim 1, said means comprising a pivoted lever, a cam member on the transfer shaft for moving said lever into engagement with

the swell, and spring means for normally holding said lever out of engagement with the swell.

In testimony whereof we have signed our names to this specification.

SAMUEL TURNER.
THOMAS EASTAUGH.
